Inventor
Edwin D. Stackhouse

UNITED STATES PATENT OFFICE.

EDWIN D. STACKHOUSE, OF COLUMBUS, OHIO.

DESIGN FOR A BADGE, EMBLEM, OR ARTICLE OF SIMILAR NATURE.

55,896.

Specification for Design.

Patented July 20, 1920.

Application filed March 15, 1920. Serial No. 366,180. Term of patent 7 years.

To all whom it may concern:

Be it known that I, EDWIN D. STACKHOUSE, a citizen of the United States, residing at Columbus, in the county of Franklin and State of Ohio, have invented a new, original, and ornamental Design for a Badge, Emblem, or Article of Similar Nature, of which the following is a specification, reference being had to the accompanying drawing, forming part thereof.

The figure is a plan view of the badge, emblem or article of similar nature showing my new design.

I claim:

The ornamental design for a badge, emblem, or article of similar nature as shown.

EDWIN D. STACKHOUSE.

Witnesses:

MARGARET E. SPENCER,
MONTGOMERY CAMPBELL.
